HAIR WAVING DEVICE

Franklin Kemp, Wesleyville, Pa.

Application January 27, 1948, Serial No. 4,639

3 Claims. (Cl. 132—36)

1

This invention relates to devices for waving hair on the human head, and particularly to an improved hair waving device of the type employing an exothermic heating element.

The primary object of the present invention is to provide a hair waving device of the above-mentioned type which is simple in construction, convenient to use, and efficient in use.

A further object is to provide a device of the above kind embodying a casing having a lower curling chamber and an upper hot vapor generating chamber, and simple means to center the heating element in the heat generating chamber and to conduct the hot vapors from the latter chamber to the curling chamber.

Another object is to provide a device of the above kind in which a heat shield for clamping the hair adjacent the scalp forms a removable bottom for the curling chamber.

The exact nature of the present invention, as well as other objects and features thereof, will become apparent from the following description when considered in connection with the accompanying drawings, in which:

Figure 1 is a side elevational view of a hair waving device constructed in accordance with the present invention,

Figure 2 is a horizontal section taken on the line 2—2 of Figure 1,

Figure 3 is a horizontal section taken on the line 3—3 of Figure 1,

Figure 4 is an end elevation looking towards the right of Figure 1,

Figure 5 is a central vertical transverse section taken on the line 5—5 of Figure 1,

Figure 6 is a central vertical longitudinal section taken on the line 6—6 of Figure 4,

Figure 7 is a perspective view of the heating element,

Figure 8 is a perspective view of the shield and curler in assembled relation,

Figure 9 is a perspective view showing how the shield is applied to a lock of hair,

Figure 10 is a perspective view of a woman's head, illustrating the manner of attaching and using a plurality of the present devices in waving the hair.

Referring in detail to the drawings, the illustrated embodiment of the invention includes a casing constructed of durable heat-insulating material to provide a lower horizontally elongated portion 5 whose interior forms a curling chamber *a*, and a vertical cylindrical upper portion 6 disposed intermediate the ends of portion 5 and whose interior forms a heat or hot vapor generating chamber *b*.

2

The portion 5 comprises a hollow open-body 7 and a heat shield 8 which clamps the hair adjacent the scalp and forms a removable bottom closure for the body 7.

The portion 6 includes an open top body 9 integral with the body 7, and a cover section 10 hinged at one side, as at 11, to the body 9 and engaged at its opposite side by a catch 12 so as to be releasably held in closed position. The shield 8 is removably held in place by spring-pressed catches 13 pivoted at 14 to the ends of body 7 and engaging keepers 15 at the ends of the shield. Suitable gaskets 16 and 17 provide air tight joints between the parts 7 and 8 and the parts 9 and 10, respectively.

The shield 8 comprises clamping plates 18 and 19 provided on their adjacent edges with yieldable jaws 20 and 21, the latter being backed by pressure-equalizing levers 22. At one end, the plate 19 carries a bar 23 to which the adjacent ends of plate 18 is hinged at 24, and which carries one of the keepers 15. Another bar 25 is hinged at one end, as at 26, to the other end of plate 19 and has a catch 27 pivoted on its other end for engagement with the other end of plate 18 to releasably secure the plates 18 and 19 together with the lock of hair gripped therebetween as shown in Figure 5 and generally well known in the art. Fixed to and rising from the plate 18 are rigid pawls 28, the purpose of which will be presently described.

The present device also includes a curler 29 adapted to have a lock of hair wound thereon and provided with the usual clamping lever 30. The enlarged circular ends 31 of the curler have ratchet teeth 32 cut in the peripheries thereof, which teeth are adapted to be engaged by the downwardly pointing free ends of pawls 28 when the curler is disposed on the shield 8 and pressed toward said pawls. By turning the curler 29, the hair may be wound thereon, as usual, and unwinding of the hair is prevented by engagement of pawls 28 with the teeth 32 of the curler. At one end, the curler 29 has a polygonal socket 33 for reception of the polygonal shank of a key used to turn the curler.

A vertical tubular post 34 is rigid with the top of the body 7 and projects into chamber *b* centrally of the latter. This post provides a passage 35 which affords communication between the top of chamber *b* and top of chamber *a*.

To generate heat by chemical reaction, I provide an exothermic heating element 36 which is a cylindrical cartridge having an axial opening 37 to snugly fit over the post 34, and which is of a size to leave a space between the same and

the side and top walls of the chamber *b* when placed in the latter. As shown, the element 36 preferably consists of a strip of absorbent material 38 provided with a backing strip 39 and containing a suitable chemical, such as calcium oxide, the strip 38 and its backing strip 39 being wound in a roll or coil.

In using the present device, the shield 8 is opened and the lock of hair *h* is introduced between the plates 18 and 19 of said shield as shown in Figure 9. The free end of the lock of hair is then secured to the curler 29 by lever 30, and the shield 8 is secured in place adjacent the scalp. The curler is then turned to wind the lock of hair thereon and when the curler contacts the shield 8, it is pressed toward pawls 28 so as to be held by the latter. By turning the curler further, the hair is placed under tension and it is so held by the pawls 28 which are engaged with the ratchet teeth 32 of the curler so as to prevent retrograde turning of the curler. The body 7 is then placed over the curler and latched to the shield 8 by catches 13. The element 36 is then dipped in fluid and placed in chamber *b*, whereupon the cover 10 is closed and latched in closed position by the catch 12. The reaction resulting from the application of moisture to the calcium oxide or the like generates sufficient hot vapors within the casing chamber *b* to effect permanency of the wave, such vapors passing from chamber *b* to chamber *a* through passage 35. At its ends, the body 7 has small inclined vent openings 40 through which excess or spent vapors may escape from chamber *a* in a direction away from the scalp. The vapors enter chamber *a* midway between its ends and flow to the ends thereof, thereby supplying the greatest heat where most needed.

From the foregoing description, it is believed that the construction, manner of use and advantages of the present invention will be readily understood and appreciated by those skilled in the art. Modifications and changes in details of construction are contemplated, such as fairly fall within the spirit and scope of the invention as claimed.

Having described the invention, what is claimed as new is:

1. A hair waving device comprising a casing having a lower horizontally elongated portion 50 whose interior forms a curling chamber and a vertical cylindrical upper portion disposed intermediate the ends of said lower portion and whose interior forms a heat generating chamber, said lower portion comprising a hollow open bottom body and a heat shield which clamps the hair adjacent the scalp and forms a removable bottom closure for said body, said upper portion including an open top body integral with the first named body and a cover section for said open

top body provided with means to secure the same in closed position, upstanding pawls carried by said shield, and a curler removably disposed in said curling chamber upon said shield, said curler having peripheral ratchet teeth at the ends thereof adapted to be engaged by said pawls for holding the curler against retrograde turning movement so as to maintain a lock of hair wound thereon under tension when passed through the shield, said casing having a vertical tubular post within the heat generating chamber providing a passage for flow of heat from the heat generating chamber to the curling chamber intermediate the ends of the latter, and an exothermic heating element disposed within the generating chamber and fitted over said post.

2. The construction defined in claim 1, wherein the casing has outwardly and upwardly inclined vents in the ends of the first named body for the escape of excess or spent heat vapors in a direction away from the scalp.

3. A hair waving device comprising a heat shield adapted to clamp on a lock of hair adjacent the scalp, a hollow body closed at the bottom by said heat shield to form a curling chamber within said body, means detachably securing said body to said heat shield, an open top body carried by the first named body and having a cover provided with means for latching the same in closed position to form a heat generating chamber within the second named body and said cover, means affording communication between the top of the heat generating chamber and the top of the curling chamber intermediate the ends of the latter, and an exothermic heating element disposed in said heat generating chamber, the means affording communication between the chambers comprising a tubular post disposed centrally of the heat generating chamber, said heating element having a central opening to snugly fit over said post.
